UNITED STATES PATENT OFFICE

FRANK C. DORMENT, OF WASHINGTON, DISTRICT OF COLUMBIA, ASSIGNOR TO THE
D & F COMPANY INCORPORATED, OF WASHINGTON, DISTRICT OF COLUMBIA, A
CORPORATION OF VIRGINIA

VAPOR-BATH CABINET

Application filed February 12, 1929. Serial No. 339,297.

This invention has special relation to that type of bath cabinet in which the patient is entirely enclosed from the neck down and subjected to a medicated vapor-bath, and one of the main objects of the invention is to provide simple means whereby, after the treatment is completed, the body odors and vapors in the cabinet may be quickly and readily removed therefrom and delivered to a pipe leading to the sewage, whereby, when the door of the cabinet is opened, there will be no escape of odors into the room in which the cabinet is located.

A further object is to provide simple means whereby the patient may be comfortably seated within the cabinet with respect to the neck-ring, this means being adjustable to adapt it to various-sized persons, the arrangement being preferably such that, when the door of the cabinet is opened, the seat upon which the patient is seated will be at the same time swung to a position out of the cabinet to enable the patient to conveniently get down from the seat, as more fully herein-after set forth.

A still further object is to provide simple means whereby the medicant will be efficaciously vaporized and mixed with water vapor and whereby also the amount of medicant vaporized may be readily adjusted, as more fully herein-after set forth.

There are still further objects of this invention which will appear in the course of the specification.

In the drawings—

Fig. 1 is a side elevation of the cabinet showing the door closed;

Fig. 2 is a plan view thereof;

Fig. 3 is a vertical sectional view taken on the line 3—3 of Fig. 2;

Fig. 4 is a vertical sectional view taken on the line 4—4 of Fig. 2;

Fig. 4^a is a detail sectional view of the sprinkler for washing out the cabinet;

Fig. 4^b is a detail vertical sectional view showing the devices for adjusting the seat-back.

Fig. 5 is a vertical sectional view taken through the lower part of the cabinet showing the vaporizer;

Fig. 6 is a view similar to Fig. 5 taken on the line 6—6 of Fig. 5;

Fig. 7 is a section taken horizontally through the cabinet;

Figs. 8, 9, 10 and 11 are views of details hereinafter described;

Referring to the drawings annexed by reference-characters, 15 designates a metal cabinet having side walls and a back wall as well as a top and bottom wall, the front side of the cabinet being open and adapted to be closed by a bowed or bulged door 16 desirably made of sheet metal and hinged at 17 to one of the corner-posts 18 (preferably hollow sheet metal) of the cabinet, a corresponding hollow metal post 18 being provided at the other side of the cabinet. A seat 19 is provided for the patient. This seat is so positioned within the cabinet that, when the patient is seated thereon, the neck of the patient will protrude through a hole 20 formed partly in the top wall of the cabinet and partly in the top wall of the door 16. The door 16 is adapted to have air-tight connection with the adjacent walls of the cabinet, so that, when it is closed and the neck-opening 20 is filled by the neck of the patient, there will be practically no opportunity for vapors to escape from the cabinet. If desired, any suitable water bandage or other device (not shown) may be placed around the neck of the patient, on the outside of the cabinet, to further prevent the escape of vapors from the cabinet.

To lock the door closed, any suitable means may be employed; I have illustrated three locking-arms 21 mounted on the ends of horizontal shafts 22 journalled in the adjacent corner-post 18 and adapted to engage lugs 23 affixed to the door. The inner ends of the shafts 22 are connected together by links 24 and arms 25 affixed to the aforesaid shafts 22, one of the shafts 22 being provided with a handle 26 within the cabinet. One of the shafts 22 is also provided with a handle 27 located outside of the cabinet. With this arrangement, the door may be locked or unlocked from the interior of the cabinet by the patient by means of handle 26, and, by means of the handle 27, the attendant may lock the door from the outside. The provision of

100

means for unlocking the door from the inside (by means of the handle 26) is desirable in order that the patient may at will—for instance, should he become frightened—readily unlock the door and release himself from the cabinet, whether or not the attendant be present in the room.

The seat 19 is supported on the upper end of a screw 28 which is threaded into an arm 29 hinged, by a vertical pintle, to one of the adjacent cabinet-posts 18, this arm 29 enabling the seat to be swung either into the cabinet or out of the same. The screw is provided with a hand-wheel 30 at its lower end to enable the seat to be raised and lowered to properly adjust it with respect to the neck-opening 20, and the seat is swivelly mounted on the arm 29 by being provided with a post 31 which fits down in the threaded passage 32 through the arm 29 and rests on the top end of the screw 28. The upper end of the post 31 is affixed to the bottom of the seat by means of a plate 32 and the point of attachment to the seat is eccentric thereto, so that the seat may be swung away from the cabinet when the door is opened to facilitate the positioning of the patient thereon. The arm 29 also assists in thus swinging the seat away from the cabinet for convenience of the patient, and, to insure the outward swinging of the seat when the door is opened, I provide a suitable connection between the seat and the door, so that, when the door is swung open, the seat will not only be turned on the post 31 as a pivot but will be carried bodily outwardly by the swinging of the arm 29. This connection with the door may be of any suitable type; I have shown a horizontal rod 33 fastened to the door, and a sleeve 34 slidably mounted on this rod, the sleeve being provided with a rod 35 which extends forwardly and has a loose connection with a slotted arm 36 depending from the seat, the purpose of the slot being to maintain connection with the rod 35 throughout the vertical adjustment of the seat 19. Any other suitable connection between the seat and the door may be used. Also, any suitable means may be used for vertically and otherwise adjusting the backrest 37 carried by the seat, to assist in making the patient entirely comfortable on the seat while positioned in the cabinet.

In the bottom of the cabinet, I place a grating consisting desirably of wooden parallel bars 38 upon which the patient may rest his feet, the rear section of this grate being hinged at 39 to enable that section to be raised to a comfortable position, the raising or adjusting of this section being accomplished by a suitable adjustable leg 40. Below the grating is located the generator for the water-vapor and medicant, the heat for generating this vapor being supplied in any suitable manner, preferably by means of

electroheating elements 41 mounted in a water-pan 42 forming virtually a depression in the bottom wall of the cabinet and being heat-insulated by means of an outer covering 43 of any suitable type. I have not shown the electrical connections for supplying current to the heating elements 41. Such connection may be of any suitable type. I have, however, shown a thermostat 44 located on the top of the cabinet in a desirable position, which may be used for controlling the temperature of the interior of the cabinet and the rapidity of vaporization of the water in the pan 42. A taletell lamp 45 may be used in connection with this thermostat for convenience and also a thermometer 46 may be used if desired.

It is desirable to keep the water in the pan 42 always at a predetermined level, and for this purpose I provide an overflow-pipe 47 whose outlet-end is connected with the drain in any suitable manner and whose inlet-end is located in a trap-cup 48 inserted in the water-supply line 49, this supply being controlled by means of a suitable manually-controlled valve 50, it being desirable that this valve be so adjusted that a constant supply of water will trickle into the trap-cup 48 and thence into the pan, the upper, inlet-end of the overflow pipe 47 determining the level of water in the pan.

The vaporization substance, preferably in a liquid form, is carried in a pan 51 mounted directly over the water pan so as to be heated by the vapor rising therefrom. This pan is supported on suitable bars or flanges 52 mounted on vertical walls 53 rising from the bottom wall of the cabinet, this medicant-pan being closed by a cover 54 which is removably held in place in any suitable manner, preferably by bolts 55. To open the pan to permit the vaporized medicant to escape into the cabinet, the pan is slid backwardly to open a gap between the inner wall 56 of the pan and the adjacent rear edge of the cover 54, a suitable packing 57 being employed to insure a vapor-tight closure when the pan is pushed up forwardly to prevent escape of the vaporized medicant. The amount of medicated vapor that is allowed to escape is determined by the position of the front wall 56 with respect to the cover 54; in Fig. 5, the pan is pushed up tightly against the end of the cover to entirely seal the medicant. To draw the pan forwardly the desired degree, any suitable device may be employed; I have shown a rock-shaft 58 journalled in the side walls of the cabinet and provided with an arm 59 which is pivotally connected to a rod 60 whose forward end is pivotally or loosely connected to a bracket 61 fastened to the back wall 56 of the pan. By rocking the shaft 58, the pan may be opened or closed to any desired degree. For thus rocking the shaft 58, I provide exteriorly a handle 62 and associate therewith

a graduated plate 63 to enable the attendant to determine to what degree the medicant is escaping into the cabinet. It will be understood that suitable packings are employed to prevent the escape of medicated vapor at any point except between the back wall 57 of the pan and the adjacent edge of the cover, and it will also be understood that when the pan 51 is opened, i. e., slid backwardly, the vapor from the water-pan 42 passes up behind the medicant-pan 51 and across rearwardly over the top of the same to thus insure discharge of the vaporized medicant out into the cabinet. Some of the water vapor may escape between the wall 56 of the pan 51 and the adjacent surrounding wall 53, as shown particularly in Fig. 5, but nevertheless there will be sufficient vapor passing up around the pan 51 to insure, as stated, the discharge of the medicated vapor. To prevent the upgoing hot vapors striking against the feet of the occupant, I provide a perforated baffle or shield 64.

After the patient has been treated and before the door is opened, it is desirable to clean out all the body odors and vapors within the cabinet. To accomplish this, I provide at one side of the cabinet a vertical tube 65 and mounted therein a water-jet 66 directed downwardly, this jet being located near the upper end of the tube. An inlet-tube 67 is provided between the cabinet and the upper end of the tube 65, at a point above the jet 66, and at the lower end of the tube an outlet connecting tube 68 is provided. By supplying water to the downwardly-directed spray-jet 66, the vapors within the cabinet will be inspirated out of the cabinet and caused to flow down the tube 65 through the continuous spray maintained therein. The spray will entrain or catch the vapors and deposit them with the water at the bottom end of the tube 65, whence they will run off with the spray water through the drainage pipe 69. An outwardly-opening gravity-valve 71 is arranged in the outlet 67 and a similar valve 72 is arranged in the inlet 68, to prevent circulation of the cabinet vapors into the tube 65 except when the spray is in operation. To prevent spray-water being carried into the cabinet at the inlet 68, I guard the same with a baffle 73. In addition to extracting of the vapors and body odors from the air in the cabinet, this spraying apparatus will cool the air and thus gradually reduce the temperature of the interior of the cabinet, thereby enabling the patient to get out of the cabinet without shock. To speed up his air-washing-and-cooling operation, I may duplicate the spray apparatus on the other side of the cabinet, as shown, and this additional spray device may obtain its water by means of a water-pipe 74 extending through the cabinet and connecting the two opposite nozzles 66; and, in order to protect the patient's hands and legs

against this cold-water pipe, I desirably enclose it in an insulating covering 75, as shown in Fig. 4. Fresh water is supplied to the nozzles 66 through the medium of a supply-pipe 76, shown particularly in Fig. 1, a valve 77 being provided for controlling the admission of water to the nozzles. 79

It is desirable at times to introduce an additional medicant or a perfume of other odoriferous substance; this may be conveniently done by attaching a valved cup 78 to the top ends of the tubes 65; and it is also desirable at times to introduce into the water in pan 42 a small quantity of medicant; this may be done through the medium of a supply-pipe 79, shown in Figs. 1 and 6, the outer end of the pipe being provided with a suitable cup 80 for containing the medicant. 80

It is desirable to wash out the cabinet after each treatment. I provide a water-sprinkler device for this purpose, this sprinkler consisting of a tube 81 (shown particularly in Figs. 4 and 4^a) extending across the rear end of the cabinet and provided with nozzles 82 extending radially from said tube 81 and having their ends all bent laterally in the same direction. Water is supplied to the interior of the tube 81 through a water-pipe 83 connected to the supply-pipe 76 and it is desirable that the tube 81 shall be rotatively mounted in the cabinet walls, so that the reaction, due to the jetting of the water out through the nozzles 82, will automatically rotate the tube 81, thus spraying the water to all parts of the interior of the cabinet and rendering it unnecessary for the attendant to manually operate the sprinkler. The projecting end of the tube 81 is provided with a hand-wheel 84 for manually rotating the tube 81 should the tube become stuck in its stuffing-boxes or the pressure of water be sufficient to cause automatic rotation of the tube 81. This sprinkler system, as is obvious, may be used to assist in quickly reducing the temperature of the interior of the cabinet should the condition of the patient require such treatment. 100 105 110

In Figs. 1 and 2, I have shown a violet-ray lamp 85 supported conveniently on the pipe 83 and flexibly connected to a suitable part of the cabinet by a coiled wire 86, for convenience in giving the patient a violet-ray treatment. 115

A convenient device for shifting the post 87 on the back-rest backwardly and forwardly to suit different-sized persons is shown in Fig. 4^b. In this arrangement, I employ a screw 88 threaded through the lower end of the post 87 and engaging a knurled nut 89 swivelled to a bracket fastened to the seat 19. 120

In accordance with the provisions of the patent statutes, I have herein described the principle of operation of my invention, together with the apparatus which I now consider to represent the best embodiments thereof, but I desire to have it understood that the 125

apparatus disclosed is only illustrative and that the invention can be carried out by other means. Also, while it is designed to use the various features and elements in the combinations and relations described, some of these may be altered and others omitted and some of the features of each modification may be embodied in the others without interfering with the more general results outlined, and the invention extends to such use.

10 What I claim as new is:

11 1. The combination with a bath cabinet having a swinging door, of a seat arrangement therefor embodying a seat, a supporting arm for said seat hingedly supported on the cabinet in such position as to swing into the cabinet as well as out of the cabinet, and means for vertically adjusting said seat on said arm, said seat being swivelled eccentrically to said arm to enable it to swing laterally independently of said arm.

12 2. The combination with a bath cabinet having a swinging door, of a seat arrangement therefor embodying a seat, a supporting arm for said seat hingedly supported on the cabinet in such position as to swing into the cabinet as well as out of the cabinet, and means for vertically adjusting said seat on said arm, means being provided whereby 25 said seat is connected to the door of the cabinet so that, when the door is opened, the seat 30 will be swung outwardly with the door.

13 3. The combination with a bath cabinet having a swinging door, of a seat arrangement therefor embodying a seat, a supporting arm for said seat hingedly supported on the cabinet in such position as to swing into the cabinet as well as out of the cabinet, and means for vertically adjusting said seat on 35 said arm, said seat being swivelled eccentrically to said arm to enable it to swing laterally independently of said arm, means being provided whereby, when the door is 40 opened, the arm supporting the seat will be 45 swung outwardly and the seat itself will be 50 swung pivotally on said support.

14 4. In combination with a bath cabinet, means for washing and cooling the air therein without opening the door embodying a 55 water-spraying device and a piping arrangement whereby the vapor-laden air is drawn out of the cabinet at the upper end thereof and subjected to the spray, to thus entrain the vapors and odors carried by the air, and 60 delivered back into the cabinet at the lower end thereof free of said odors and vapors.

15 5. In combination with a bath cabinet, means for washing and cooling the air therein without opening the door embodying a 65 water-spraying device and a piping arrangement whereby the vapor-laden air is drawn out of the cabinet at the upper end thereof and subjected to the spray, to thus entrain the vapors and odors carried by the air, and 70 delivered back into the cabinet at the lower 75 end thereof free of said odors and vapors.

76 end thereof free of said odors and vapors, drainage means being provided for the vapor-laden water.

77 6. In combination with a bath cabinet, means for washing and cooling the air therein 78 without opening the door embodying a water-spraying device and a piping arrangement whereby the vapor-laden air is drawn 80 out of the cabinet at the upper end thereof and subjected to the spray, to thus entrain the vapors and odors carried by the air, and delivered 85 back into the cabinet at the lower end thereof free of said odors and vapors, an outlet-valve being provided at the air-outlet at the top and an inlet-valve being provided at the air-inlet at the bottom.

86 In testimony whereof I hereunto affix my signature.

87 FRANK C. DORMENT.
